UNITED STATES PATENT OFFICE

161,791

COMBINED HIGH CHAIR AND LADDER

Philip R. Schilling, Benton Harbor, Mich.

Application March 16, 1950, Serial No. 8,571

Term of patent 14 years

(Cl. D15—8)

To all whom it may concern:

Be it known that I, Philip R. Schilling, a citizen of the United States, residing at Benton Harbor, Berrien County, Michigan, have invented a new, original, and ornamental Design for a Combined High Chair and Ladder, of which the following is a specification, reference being had to the accompanying drawing, forming a part thereof, in which:

Figure 1 is a perspective view of a combined high chair and ladder embodying the design of the present invention;

Figure 2 is a rear elevational view;

Figure 3 is a top plan view;

Figure 4 is a side elevational view; and

Figure 5 is a front elevational view.

I claim:

The ornamental design for a combined high chair and ladder, as shown.

PHILIP R. SCHILLING.
